(57) **CLAIM**

The ornamental design for a computer case, as shown and described.

DESCRIPTION

FIG. 1 is a perspective view of a computer case according to the invention;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The rear elevational view and the bottom plan view of the computer case are shown for illustrative purpose only. The features shown in dashed lines in the rear elevational view and the bottom plan view are functional features, which are not visible during the normal use, and form no part of the claimed design. The features shown in dashed line in the front elevational view, the right side elevational view, and the left side elevational view are shown for illustrative purpose only and form no limitation to the claimed design.
